ROTARY PUMP OR MOTOR

Ernest H. Garwood, Long Beach, Calif.

Application March 15, 1956, Serial No. 571,685

1 Claim. (Cl. 103—162)

This invention relates to a novel pump or motor of the rotary type, and in which the valving structure between the rotor and the body of the pump or motor consists of a portion of the body itself against which the rotor is accurately fitted, thus eliminating all additional valve structures which might otherwise be required.

Another object of my invention is to provide a novel arrangement of cylinders within the rotor and a pair of pistons in each cylinder whereby an opposed piston construction is provided, thus producing greater balance in the motor or pump eliminating vibration to a large extent.

Another object of my invention is to provide a novel means of reciprocating the pistons in the rotor by means of an internal cam track within the body of the pump or motor.

Still another object of my invention is to provide a novel pump or motor of the character stated, in which there are a minimum number of parts, and thus also producing a pump or motor which is efficient and which will operate to produce a considerable amount of power per pound of weight.

Other objects, advantages and features of invention may appear from the accompanying drawing, the subjoined detailed description and the appended claims.

In the drawing:

Figure 1 is a vertical sectional view taken on line 1—1 of Figure 3.

Figure 2 is a sectional view taken in line 2—2 of Figure 3.

Figure 3 is a sectional view taken on line 3—3 of Figure 1.

Referring more particularly to the drawing, my motor or pump consists of a housing or body 1 which includes two complementary units 2 and 3. The units 2 and 3 are bolted together by means of the matching peripheral flanges 4, substantially as shown. The units 2 and 3 are hollow, that is, they are substantially cup-shaped, and the unit 2 is provided with a central annular hub 5. The hub 5 projects inwardly and the purpose of this hub will be subsequently described. The periphery of the hub is accurately machined for the purpose of receiving the rotor, as will be subsequently described. The part 3 is formed with a cam track 6 on the inside thereof and this cam track is formed with two or more high lobes, as well as two or more low lobes, for the purpose of causing reciprocation of the pistons within the rotor, as will be subsequently described. The part 2 is provided with a similar cam track 7 which is identical in shape to the cam track 6, and the high and low lobes of the two cam tracks are arranged opposite each other for a purpose to be subsequently described. The hub 5 is formed with two or more intake ducts 8 and 9 which are drilled in the hub and extend radially outward to an enlarged fan-shaped port 10—11, respectively. Similarly, a pair of outlet ducts 12—13 are drilled in the hub 5 and these outlet ducts extend from a similarly fan-shaped port 14 and 15, respectively. All of these ports are at the periph-

2

ery of the hub 5 and are thus adjacent to the rotor, as will be subsequently described.

A rotor 16 is mounted on a shaft 17 which is suitably journaled in the hub 5 of the housing 1, substantially as shown. The rotor 16 is formed with an annular peripheral ring portion 18 which will be termed the cylinder portion of the rotor. The inner surface of the cylinder portion of the rotor is accurately machined to fit the outer machined surface of hub 5. Thus the adjacent moving part of the rotor 16 to the hub 5 is so constructed that it will effectively seal off against the hub, thus preventing leakage between the hub and the rotor at this point. The outer peripheral surface of the rotor 16 may also be accurately machined to fit the inside of the complementary housing parts 2 and 3. The cylinder portions 18 of the rotor 16 are formed with a plurality of peripherally arranged and laterally extending cylinders 19, and each cylinder extends transversely through the cylinder portion 18 of the rotor. In each cylinder 19 I provide a pair of pistons 20—21 which are thus opposed and the pistons are reciprocally mounted in the cylinders and move laterally with respect to the rotor 16. Reciprocation of the pistons 20—21 is accomplished by means of the cam tracks 6 and 7. Each piston is provided with a finger 22 which projects from the outer end of each piston and extends around the back of the cam track 6 and 7. An appropriate bearing or ball 23 on the finger 22 reduces friction of the finger against the actuating cam. Similarly, a bearing or ball 24 on the end of each piston bears against the inner flat face of the respective cams 6 or 7, thus causing the pistons to be reciprocated as the rotor 16 moves with relation to the cam tracks 6 and 7. The innermost surface of each of the cams 6 and 7 move the pistons in one direction, while the fingers 22 move the pistons in the opposite direction. This is evident since both the innermost and outermost cam surfaces of the cam tracks 6 and 7 are both engaged by each of the pistons. The cam tracks 6 and 7 are, furthermore, so arranged as to their high and low points or lobes that the pairs of pistons 20—21 in each cylinder 19 will be moved inwardly and outwardly together, thus creating a pumping action within the respective cylinders, or if a fluid pressure is exerted on the intake ducts a rotating force will be exerted on the rotor 16. Each cylinder 19 is provided with an outlet port 25 which permits air or fluid to move into the fan-shaped ports 15 and thence to the outlet ducts.

In operation.—Assuming that the device is to be used as a pump, power is applied to the shaft 17 which causes the rotor 16 to rotate within the housing 1. The cam tracks 6 and 7 are stationary and, consequently, as the rotor 16 moves with relation to the cam tracks the pistons 20 and 21 will be reciprocated within the cylinders 19, since the pistons engage both the outer and the inner cam surfaces of the tracks 6 and 7. Reciprocation of the pistons 20 and 21 will cause fluid to be pumped through the outlets 25, thence into the ports 14—15 and out through the ducts 12 and 13. This is accomplished on the inward movement of the pistons 20 and 21. The outward movement of the pistons will cause fluid to be drawn into the cylinders 19 from the ports 10 and 11 in a similar manner, as previously described.

Having described my invention, I claim:

A rotary pump or motor comprising a housing including two complementary units, a hub on one of said units, a shaft extending into the housing and through said hub, a rotor on the shaft and positioned within the housing, said rotor having an accurate fit on the hub and extending over the hub, a plurality of peripherally arranged and longitudinally extending cylinders in the rotor, said cylinders extending entirely through the rotor and being open at both ends thereof, a pair of pistons in each of the cylinders, one end of each of the pistons projecting from

the cylinders, a cam track within each of said units, the projecting end of the pistons engaging said cam track to reciprocate the pistons, a finger projecting from each piston, said fingers engaging a face of the cam track opposite the face engaged by the pistons, said hub having fan-shaped ports at the periphery thereof and adjacent said rotor, said housing having an intake and an outlet duct therein, said ducts extending through the hub to the fan-shaped ports in the hub, and said rotor having outlet ports therein extending from each of the cylinders, said outlet

10

ports registering with the inlet and outlet ducts successively as the rotor rotates.
